(57) **CLAIM**

The ornamental design for double action OTF automatic knife as shown and described.

DESCRIPTION

FIG. 1 is a frontal perspective view of a double action OTF automatic knife embodying the new design, wherein the blade is in the retracted position.

FIG. 2 is a rear perspective view thereof.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof.

FIG. 8 is a bottom plan view thereof.

FIG. 9 is a frontal perspective view of the double action OTF automatic knife of FIGS. 1-8, wherein the blade is in the extended position.

FIG. 10 is a rear perspective view of the double action OTF automatic knife of FIG. 9.

FIG. 11 is a front elevation view of the double action OTF automatic knife of FIG. 9.

FIG. 12 is a rear elevation view of the double action OTF automatic knife of FIG. 9.

FIG. 13 is a left-side elevation view of the double action OTF automatic knife of FIG. 9.

FIG. 14 is a right-side elevation view of the double action OTF automatic knife of FIG. 9.

FIG. 15 is a top plan view of the double action OTF automatic knife of FIG. 9; and,

FIG. 16 is a bottom plan view of the double action OTF automatic knife of FIG. 9.

Shading forms no part of the claim.

1 Claim, 16 Drawing Sheets
